COMBINED KNIFE AND RECEPTACLE THEREFOR

David Turner Mairs, East Sydney, New South Wales,
Australia

Application July 8, 1954, Serial No. 31,348

Term of patent 14 years

(Cl. D22—3)

FIG. 2.

In the accompanying drawing, Figure 1 is a perspective view of a combined knife and receptacle therefor showing my new design; and Figure 2 is an exploded perspective view of the component parts thereof.

I claim:

The ornamental design for a combined knife and receptacle therefor, substantially as shown.
